UNITED STATES PATENT OFFICE.

BRUCE FORD, OF PHILADELPHIA, PENNSYLVANIA.

CONNECTOR-PULLER FOR BATTERY-TERMINALS.

1,147,932.

Specification of Letters Patent. Patented July 27, 1915.

Application filed August 22, 1911. Serial No. 645,416.

To all whom it may concern:

Be it known that I, BRUCE FORD, a citizen of the United States, residing at the city of Philadelphia, in the county of Philadelphia and State of Pennsylvania, have invented a certain new and useful Connector-Puller for Battery-Terminals, of which the following is a specification.

Objects of the present invention are to provide a portable tool for disconnecting the connector straps from the plate terminals to which they are attached as by lead burning or the like in such manner that the straps and terminals are uninjured and are fit for re-use; to adapt the tool for use in connection with such different forms of straps as are commonly employed; and to provide a compact, strong and inexpensive connector puller.

The invention will be claimed at the end hereof but will first be described in connection with the embodiment of it which I have selected from various embodiments as being what I consider the best embodiment of it now known to me.

In the drawings Figure 1, is a view, principally in central section, of a tool embodying features of the invention. Fig. 2, is a front view of the tool with parts broken away. Fig. 3, is a sectional view taken on the line 3, of Fig. 1, looking in the direction of the arrow, and Figs. 4 and 5, are perspective views of parts of straps showing forms thereof in connection with which the tool can be used.

In the drawings 1, is a housing having generally the form of the half of a hollow cylinder although the form may of course be varied and changed.

2, is a handle projecting from the rear of the housing. At the bottom of the housing there is a post receiving notched jaw 3. The notch of this jaw is open so that the post *a*, and strap *b*, can be inserted laterally into the housing. The housing is provided at its top with a tapped opening 4, for a purpose to be presently described. Within the housing there are guide ways 5, which are shown to consist of pins extending from and secured to the top and bottom walls.

6, is a clamping jaw or guide collar and it is movable on the guide ways 5, and is prevented by these guide ways from turning. This member 6, is provided with a punch shank opening 7, and with a punch head re-

cess or cavity 8. The member 6, is also provided with a notch 9, which accommodates a stripper 10, consisting of a rod having its ends secured to the walls of the housing.

11, is a spring operating on the jaw or collar 6, and seated on the top of the housing or on an appropriate part connected therewith.

12, is a screw or pressure plug arranged in the tapped opening 4. 65

13, is a punch having its head 14, arranged for movement into and out of the cavity or recess 8. The head of the punch may be provided with a projecting centering point 15. The shank of the punch works freely 70 through the opening 7, and there are means for revolubly connecting the screw or pressure plug with the shank. These means are shown to comprise a ball 16, fixed to the shank of the punch and arranged in a 75 socket 17, fixed to the screw 12.

18, is a wear plate that may be interposed between the ball and the screw.

19, is a handle movably inserted through an opening in the head of the screw 12. 80

In use the post and strap *a* and *b*, are inserted into the tool or the tool is applied to them in such manner that the post is received by the notched jaw 3, and the strap rests upon the inner surface of the jaw 85 which may be recessed or faced as at 20, for its reception. When this is done the jaw or collar 6, is held away from the jaw 3, against the compression of the spring 11, by the punch, the head of which rests on the bottom of the cavity 8. To separate the strap and post, the screw or pressure plug 12, is advanced into the housing by means of the handle 19. The result of this is that the jaw or collar 6, is brought by the action of 90 the spring 11, to bear upon the top part of the strap and by reason of the concave shape of the cavity 21, which receives the strap, the latter as well as the post *a*, are centered and the strap is held against the jaw 3, while the post is free in the notch of that jaw. After the strap and post have been thus properly positioned and held the continued turning of the screw 12, causes the head of the punch to be projected from 100

the cavity 8, and to bear upon the top of the post *a*, and to exert such pressure upon the post that it is detached from the strap or, more accurately, pushed out of the hole in the strap in which hole it has been pre- 110

viously inserted and secured by burning or puddling. The point 15, on the head of the punch insures accuracy of the operation of the punch in respect to the center of the post. The screw is then retracted from the housing so that the punch is drawn back into the cavity 8, and engages the collar or jaw 6, and moves it away from the jaw 3. If the strap should stick to the jaw or collar 6, the stripper 10, which overlies the strap prevents it from moving with the punch or collar so that the strap is detached and cleared. The operation of the tool in connection with the form of strap end *c*, is the same as has been described. The cavity or recess 21, coöperates with the other parts in each case to center the strap and post properly in respect to the parts which operate upon them.

20. What I claim is:

1. A connector puller for battery terminals comprising the combination of an open-sided receiving jaw and a guide collar movable the one in respect to the other, a spring 25 for actuating one of said parts, a screw plug, and a punch revolubly connected with the screw plug and having sliding connection with said collar whereby it is adapted to restrain said spring and to be projected 30 through the collar, substantially as described.
2. A connector puller for battery terminals comprising the combination of receiving jaws adapted to receive between them a post and connector end, a spring tending to shift said jaws to center and clamp the post and connector end, a screw, and connections for restraining said spring to permit of the insertion of the connector end and post and 40 for releasing said spring to permit the jaws to center and clamp the connector end and post and for detaching the post from the clamped connector end, substantially as described.
45. 3. A connector puller for battery terminals comprising the combination of a housing having an open-sided receiving jaw and provided with guide ways, a guide collar slidable on said ways and provided with a punch shank opening and with a punch 50 head cavity, a spring tending to shift said collar toward said jaw, a screw plug, and a headed punch having its shank arranged through said shank opening and revolubly 55 connected with the screw plug and having its head occupying said cavity and adapted

to be projected therefrom, substantially as described.

4. A connector puller for battery terminals comprising the combination of a housing having an open-sided receiving jaw and guide ways and a stripper, a guide collar 60 slidable on the guide ways and coöperating with the stripper, a spring for actuating the collar, a screw plug, and a headed punch 65 revolubly connected with the plug and having its head arranged in engagement with the collar and adapted to be projected therefrom, substantially as described.

5. A connector puller for battery terminals comprising the combination of a housing having an open-sided jaw and provided with lengthwise and crosswise arranged 70 rods constituting guide ways and a stripper, a guide collar slidable in respect to said 75 rods, a spring for the collar, a screw plug arranged through the wall of the housing, and a headed punch revolubly connected with the screw plug and having its head in engagement with the collar and adapted to 80 be projected therefrom, substantially as described.

6. A connector puller for battery terminals comprising the combination of a pair 85 of jaws of which one is movable, a spring for actuating the movable jaw, a screw, and a punch adapted to be actuated by the screw and to be projected through said movable jaw and to engage the same, substantially as described.

7. A connector puller for battery terminals comprising the combination of a fixed jaw, a punch and a guide collar movable in respect to each other and to the jaw, and devices for operating the collar in advance 95 of the punch in approaching the fixed jaw.

8. A connector puller for battery plates comprising the combination of a fixed jaw, a punch, a guide collar in respect to which the punch is projectable and retractable, a 100 spring tending to move the collar toward the jaw, the punch being provided with means for resisting the spring, and means for projecting the punch from the collar toward the fixed jaw.

In testimony whereof I have hereunto signed my name.

BRUCE FORD.
